UNITED STATES PATENT OFFICE.

JOSEPH G. WARE, OF DAYTON, OHIO.

DESIGN FOR AN ORNAMENTAL NUT-LOCK.

SPECIFICATION forming part of Design No. 20,237, dated October 28, 1890.

Application filed May 20, 1890. Serial No. 352,540. Term of patent 14 years.

To all whom it may concern:

Be it known that I, JOSEPH G. WARE, a citizen of the United States, residing at Dayton, in the county of Montgomery and State of Ohio, have invented and produced a new and original Design for Ornamental Nut-Locks, of which the following is a specification, reference being made to the accompanying drawing, forming a part thereof.

10 The accompanying drawing represents a plan of my device for an ornamental nut-lock, showing the outline or configuration of the same.

As shown in the drawing, the figure in outline generally resembles an oak-leaf, having projecting from its leaf-like portion A the portion C, which corresponds in a measure to the stem of the leaf, and the curved projecting portions D, which have round ends cor-

responding approximately to the lobes of an 20 oak-leaf or similar leaf. Through the center of the leaf-like portion A is formed a circular opening or perforation B, as shown.

The leading feature of my design consists of the leaf-like or foliated outline of the plate 25 which forms the nut-lock.

What I claim is—

The design for a nut-lock herein shown and described, the same comprising a plate having the shape and configuration generally of 30 a centrally-perforated oak-leaf, substantially as set forth.

In testimony whereof I affix my signature in presence of two witnesses.

JOSEPH G. WARE.
